UNITED STATES PATENT OFFICE

CHARLES T. WHITESCARVER, OF NEW YORK, N. Y., ASSIGNOR TO UNIVERSAL FORM CLAMP CO., OF CHICAGO, ILLINOIS, A CORPORATION OF ILLINOIS

FORM CONSTRUCTION FOR CONCRETE FLOORS

Application filed April 20, 1929. Serial No. 356,800.

This invention relates to improved means for supporting and assembling concrete floor molds.

In building constructions, where concrete floors are to be erected, it is customary to build a mold for the lower surface of the floors and to support this mold either from the structural steel beams or upon shoring erected on the floor below. Flexible tie bands have been used extensively in suspending the floor forms from the structural shapes.

It is, of course, preferable to suspend the floor mold from the structural beams in order to leave the floor below free from obstructions which impede the progress of the workmen.

Molds for concrete floors generally comprise a plurality of substantially parallel channel sections, built around the structural beams, and intervening slab sections which span the spaces between the beams. Heretofore, in the assembly of floor molds it has been customary generally to support the beam sections and slab sections independently of one another. Such prior constructions required a large amount of tie bands and clips for suspending the separate beam sections and slab sections from the structural shapes.

The main objects of this invention are to provide a form clamp having an improved rail adapted to span the space between adjacent beams for supporting a plurality of mold sections; to provide improved cleats on said rail for attachment to the tie bands and for clamping the side sections of the beam molds to the soffit sections; to provide cleats of this kind which are adjustable so as to accommodate beam molds of different widths; to provide improved fastening means for clamping said cleats to the tie bands and to said rail; and to provide an improved form clamp which is simple in construction and whereby the floor forms may be readily assembled and dismantled.

An illustrative embodiment of this invention is shown in the accompanying drawings, wherein:—

50 Figure 1 is a fragmentary plan of a floor

mold to which improved clamps are applied; some of the slab sections being omitted.

Fig. 2 is a vertical section, taken on the line 2—2 of Fig. 1.

Fig. 3 is an enlarged fragmentary vertical section, taken on the line 3—3 of Fig. 1.

Fig. 4 is a vertical section of one of the clamps; the view being taken on the line 4—4 of Fig. 3.

In the form shown in the drawings, the apparatus is arranged for casting a concrete floor made up of horizontal slabs and substantially parallel beams in which structural steel shapes 1 are embedded. In such a construction, the bottom of the floor slabs and the sides of the concrete beams are formed by means of slab molds 2 and channel-shaped beam molds 3, respectively.

In the form shown, the slab molds 2 are supported on the beam molds and comprise planks 4 mounted on joists 5, which are arranged on edge and disposed transversely of the beams 1.

The beam molds 3 comprise the usual soffit sections 6 and side sections 7 arranged to form channels surrounding the structural shapes 1. Mounted on the outer faces of the side sections 7, are the usual vertical battens 8, to which are secured kicker strips 9 extending longitudinally of the side sections 7. The side sections 7 are spaced the required distances from the structural beams 1 by means of spacing clips 10 embracing the lower flanges of the beams.

Suspended from the structural beams 1, are flexible tie bands 11 which extend downwardly between the abutting faces of the soffits 6 and side sections 7. The upper ends of the tie bands 11 are secured to the upper flanges of the beams 1 by clips 12 and the lower ends of the bands are detachably secured to the improved form clamps which support the mold sections.

In the embodiment illustrated, each of the improved form clamps comprises a rail 13, on which is adjustably mounted two pairs of cleats 14. The rail 13 preferably consists of a T-bar of greater length than the distance between two adjacent beams, so as to be adapted to span the intervening space

and support the molds of both beams. The top flange of the T-rail 13 provides a flat bearing surface for the soffit sections 6, which are supported thereon directly below 5 the structural beams 1.

In the form shown, each of the cleats 14 comprises a base 15, having a guide slot 16 of T-shaped cross section extending therethrough for receiving the rail 13. Also extending through the base 15, is a guideway 17 for receiving the flexible tie band 11. The guideway 17 communicates with the slot 16, so as to permit the band 11 to engage the top flange of the rail 13.

15 Threaded in the base part 15, is a set screw 18, which projects downwardly into the guideway 17 for clamping the cleat to the tie band and to the rail 13.

The top surface of the base 15 provides 20 a substantially flat shelf 19 for supporting the side sections 7, battens 8 and kicker strips 9 of the beam mold. A bracket 20 projects upwardly from the base 15 for engagement with the outer face of the kicker 25 strip.

To assemble a floor mold of this construction, the rails 13 of the improved clamps are disposed in staggered relation to one another as illustrated in Fig. 1. Each of the 30 rails 13 is suspended from the two adjacent beams 1 by only two tie bands 11, which are preferably secured to the two inner cleats 14 of the clamp.

After the mold sections 7 have been placed 35 on the shelves 19 of the two inner cleats 14 of each clamp, the soffits 6 may be placed over the outer ends of the clamps and slid into position below the beams 1.

When the soffits 6 have been positioned 40 properly, the other mold sections 7 may be placed on the outer cleats 14 of the clamps so as to complete two adjacent beam molds. The outer cleats of each clamp are preferably not attached to any tie bands. When 45 the beam molds are assembled, the outer cleats 14 of the clamps are moved inwardly to press the side sections 7 against the soffits 6 and the cleats are clamped in effective position by the set screws 18. After the beam 50 molds have been assembled the slab molds 2 are constructed to span the intervening spaces.

To dismantle a floor form of this improved construction, the set screws 18 are 55 loosened to release the cleats 14. When the cleats are released, the clamps and mold sections may be readily lowered. If desired, the projecting portions of the tie bands 60 may be cut off flush with the concrete.

Although but one specific embodiment of 65 this invention has been herein shown and described, it will be understood that numerous details of the construction shown may be altered or omitted without departing

from the spirit of this invention as defined by the following claims.

I claim:

1. In a device of the class described, the combination with a pair of substantially parallel structural shapes spaced apart, a pair of flexible tie bands suspended from said structural shapes, of a form clamp comprising a rail spanning the space between said structural shapes, a pair of beam molds supported on said rail, and a plurality of cleats adjustably mounted on said rail and arranged in pairs for embracing said beam molds, one of said tie bands being secured to a cleat in one of said pairs, the other of said tie bands being secured to a cleat in the other of said pairs.

2. In a device of the class described, the combination with a pair of substantially parallel structural shapes spaced apart, flexible tie bands suspended from said structural shapes, of a form clamp comprising a rail spanning the space between said structural shapes, soffit sections supported on said rail below said structural shapes, cleats mounted on said rail and adjustable longitudinally thereof, side sections supported on said cleats and held thereby in abutting relation to said soffits, slab sections supported on said side sections, said cleats having guideways therein for receiving said tie bands, and means on said cleats for clamping said cleats to said tie bands and to said rail.

3. A device of the class described comprising a rail adapted to support a mold section, tie elements, adapted to support said rail, a pair of cleats mounted on said rail and adjustable longitudinally thereof, said cleats having guideways extending therethrough for receiving the tie elements, and means on said cleats for clamping said cleats to said tie elements and to said rail.

4. A device of the class described comprising a rail adapted to support a mold section, tie elements adapted to support said rail, a pair of cleats mounted on said rail and adjustable longitudinally thereof, shelves on said cleats adapted to support other mold sections, said cleats having guideways extending therethrough for receiving the tie elements, and means on said cleats for clamping said cleats to said tie elements and to said rail.

5. A device of the class described comprising a T-rail adapted to support mold sections, a plurality of cleats slidably mounted on said rail and having guideways extending therethrough longitudinally of said rail, flexible tie bands extending through said guideways, shelves on said cleats for supporting other mold sections, and fastening means on said cleats for clamping said cleats to said tie bands and to said rail.

6. A device of the class described com-

prising a rail adapted to support a mold section, a tie element for supporting said rail, a cleat mounted on said rail and adjustable longitudinally thereof, said cleat having a guideway therethrough for receiving said tie element, and means for clamping said cleat to said rail and to said tie element.

7. A device of the class described comprising a T-rail adapted to support a mold section, a cleat slidably mounted on said rail and having a guideway extending therethrough, a flexible tie band extending through said guideway, and a screw arranged to clamp said cleat to said tie element and to said rail.

15 Signed at Chicago this 13th day of April, 1929.

CHARLES T. WHITESCARVER.
